KNITTING MACHINE AND METHOD

Hyman M. Zippel, Philadelphia, Pa.

Application December 3, 1937, Serial No. 177,845

15 Claims. (CL 66—65)

This invention relates to a knitting method and machine, and has particular reference to a method and machine for knitting gloves.

Heretofore, gloves, when knitted in tubular form, have been knitted sectionally, that is, the palm portion has been knitted and then the palm portion has been transferred to another machine for successive operations in the formation of the fingers, each finger being formed separately. The necessity for transfer and the use of considerable time for the formation separately of the fingers of the glove have substantially reduced the rate of formation of these gloves and hence made such gloves costly.

15 In accordance with the present invention, gloves are made by a novel process continuously, one after the other, on a machine without the necessity for any transfer operations and in a fashion permitting the fingers of the gloves to be 20 knit simultaneously. In the preferred embodiment of the invention, this is carried out by first knitting in tubular form the wrist portion of a glove, then widening to form the palm. After a portion of the palm has been knit to the point 25 where the thumb portion of the glove should begin, knitting continues with the addition of another yarn in such fashion that in alternate courses the yarn which has been knitting the palm continues to knit the palm and in intermediate 30 courses the other yarn forms the thumb portion continuously with the palm on certain of the needles which had previously knit the palm. Then when the position is reached for the formation 35 of the other fingers, another sequence takes place whereby in every other course tubes are simultaneously produced to form the thumb, second and fourth fingers and in intermediate courses tubes are produced to form the first and third fingers. When a tube sufficiently long to form 40 the thumb has been completed, the formation of the thumb tube is interrupted and later the formation of the fourth finger tube is interrupted. Finally, when the three intermediate finger tubes 45 are completed the formation of the wrist again begins, and the operation is repeated. Thus the final product is a series of gloves which may be cut apart and finished by stitching.

The accomplishment of this method, which is 50 the primary object of the invention, together with other objects of the invention, relating particularly to the provision of a machine for carrying out the improved process and capable of other uses, as will be obvious hereafter, will become apparent from the following description, read in

conjunction with the accompanying drawings, in which:

Figure 1 is a vertical section taken through the improved machine as set up for the formation of gloves which are illustrated therein;

Figure 2 is a vertical section taken on the plane indicated at 2 in Figure 1;

Figure 3 is a vertical section taken on the plane indicated at 3 in Figure 1;

Figure 4 is a vertical section taken on the plane indicated at 4 in Figure 1;

Figure 5 is a plan view of certain controlling devices for determining the yarns which are to be knit;

Figure 6 is a perspective view showing a controlling cam plate, also illustrated in Figures 1 and 5;

Figure 7 is a diagram illustrating the throws of the various yarn-carrying fingers; and

Figure 8 is a diagram illustrating the various 20 sequences of operations involved in the formation of a glove.

The machine illustrated in the present application is of the general type referred to in my prior Patent 1,992,982, dated March 5, 1935. While in 25 said patent the machine illustrated is of large size designed to produce large sections of cloth, the present machine may be considered substantially a modification of that machine on a very much smaller scale. While in the machine of 30 the patent particular stress is laid on the formation of designs of elaborate character, it will be obvious that this type of machine by the proper control of the needles may be made to form tubes of both simple and complex designs, and the controlling devices for the needles and cooperating elements for the formation of such designs may be utilized in the machine of the present application. Accordingly, the needle controls are herein 35 illustrated only in conventionalized fashion, it being understood that so far as details are concerned the features described in my prior patent may be used with such well known modifications and under such well known limitations as are consistent 40 with the formation of tubular fabric. For convenience in describing the present invention, it will be considered that the machine of the present application is being used to knit plain tubular fabric. It will also be clear that a number of these 45 machines may be associated with common controls for simultaneous production operations.

The machine comprises a frame 2 carrying needle supports 4 within which there reciprocate two banks of needles 6 arranged in intersecting rela- 50

tionship, as indicated in Figure 4. Selection of needles for knitting is accomplished by the use of a jacquard mechanism of the type illustrated in my prior patent and conventionally illustrated at 1. This jacquard mechanism, acting in conventional fashion, raises needles which are to take yarn and leaves downwardly the needles which are not to take yarn in the formation of any course. By this jacquard mechanism, the alternate formations of finger courses are effected as well as widening from the wrist to the palm, etc. The jacquard mechanism may also function for patterning in the usual fashion. The needles are controlled in the usual fashion by cams in carriers 8 arranged to be reciprocated longitudinally of the machine along guideways 9. The carriers 8 are joined by means of a yoke 10 extending upwardly over the yarn carrying mechanism. Reciprocation is effected through conventional driving means not illustrated.

Brackets 12 and 14 carry cam blocks 16 and 18 in which are formed cam grooves 20 and 22 as illustrated in Figure 1. Within these cam grooves there extend pins 24 and 26 carried by a set of yarn carrier guide rods 28, there being four such rods 28 and corresponding sets of cam grooves 20 and 22 formed as indicated hereafter. As illustrated in Figures 3 and 4, the yarn carrier guide rods 28 support for longitudinal movement thereon a number of yarn carriers 30, 32, 34, 36, 38 and 40. The carriers 30 and 40 are mounted on individual rods 28, while the pair of carriers 32 and 34 are mounted on the third rod and a pair of carriers 36 and 38 on a fourth rod. These various carriers support yarn feeding fingers 42 so arranged that certain of the fingers may clear others if one or the other groups is raised by reason of the longitudinal movement of the corresponding guide rods 28, so as to cause the pins 24 and 26 to ride into the upwardly extending portions of the cam grooves 20 and 22. Thus if the rods carrying all the carriers except 30 are raised the carrier 30 may move with its yarn finger 42 in active position, moving below the other yarn fingers which are raised. The various operations attendant upon selection of yarn fingers will be made clear hereafter in discussing the specific formation of a certain product.

A series of levers 44 are pivoted on an extension of the bracket 14 and are joined at 46 to their corresponding rods 28, there being one of such levers for each rod. Each lever, furthermore, has pivoted to it at its upper and lower ends, respectively, plungers 48 and 50, which project to the right of the bracket 14 as viewed on Figure 1. There are provided four vertically slideable members 52 each corresponding to one of the rods 28 and each arranged to be reciprocated vertically by means of an individual lever 54 arranged to be selectively acted upon by lugs on a pattern chain 56. The four pattern chains are advanced simultaneously, passing over simultaneously driven sprockets and being controlled by a pattern mechanism of conventional type so as to have step by step movements. At its upper end each of the slides 52 supports a plunger 58 pressed toward the right as indicated in Figure 1 by a spring 60. A block 62 is arranged to reciprocate on a pair of rods 68 and carries four pairs of upper and lower adjustable abutment screws 64 and 66 arranged to be aligned with the various plungers 58. Motion is imparted to the slide 62 through the medium of a rocking lever 70 engaging a cam groove 72 in a cam 74 carried by the main shaft 75 of the machine. By this means

the slide 62 is reciprocated once in the formation of each complete course by the machine.

The yoke 10 has pivoted to it a set of levers 78, in the present case six, one for each yarn carrier. These levers are jointed so as to have a yielding free end 80 normally pressed downwardly by a spring 82. Each lever 78 is normally urged in a clockwise direction as viewed in Figure 1 by a spring 86. The right hand end of each lever is formed as a follower adapted to ride upon various lugs hereafter referred to carried by a cam plate 88. Cams 90 and 92 are provided on the rods 28 for the purpose of releasing the yielding ends 80 of the levers 78 from the notches 84 in the tops of the yarn carriers within which they engage for moving said carriers. Lateral clearances are provided so such release may take place.

In order to determine the yarn carriers which are to be reciprocated there is provided on the yoke 10 a rocking lever 94 to the ends of which are pivoted slides 96 and 98, the former being secured to the plate 88 as indicated in Figure 5. The slide 96 is provided at its outer end with a series of steps 100, while the slide 98 is provided with a similar series of steps 102. A set of pins 104, eight in number and staggered vertically, as indicated in Figure 1, are carried by a vertical slide 106 arranged to be reciprocated through a push rod 110 by means of a lever 108 which is arranged to ride upon lugs of another pattern chain driven in unison with the pattern chains 56. As indicated in Figure 6 rods 104 are aligned with the various steps 100 and 102 so that any selected step of either of these sets may engage with its corresponding pin 104 by the proper vertical positioning of the sets of pins. Cam lugs 112 on the plate 88 cooperating with the right hand ends of the levers 78 determine the engagement of the various yarn carriers for reciprocating movement.

The improved method of knitting a glove will be most readily understood by considering the various portions of a glove illustrated in Figure 1 and the diagrammatic illustrations of Figures 7 and 8, taken particularly in conjunction with the cam arrangement illustrated in Figure 6 and the feeding finger arrangement of Figure 4. The various feeding fingers are desirably associated in the manner illustrated for the sake of simplicity. The carrier 30, mounted on the left hand bar illustrated in Figure 4, carries the palm yarn. The carriers 32 and 34, mounted on the second bar illustrated in Figure 4, carry respectively the fourth and second finger yarns. The carriers 36 and 38, mounted on the third bar, carry respectively the third and first finger yarns. The carrier 40, mounted on bar 28, carries the thumb yarn.

As viewed in Figure 1, the bar which supports the palm yarn carrier 30 is arranged to rise as it moves to the left so as to move its carrier out of operation in a left hand movement and restore it to operation by a right hand movement. The remaining bars, with the exception of the thumb carrier bar are similarly arranged. The thumb carrier bar has an opposite action, moving to the right to go up out of action and to the left to go down into action. Due to the fact that carriers 32 and 34 are mounted on the same bar, they go into or out of action simultaneously. The same is true of the carriers 36 and 38.

Referring to Figure 7, there are indicated diagrammatically therein by the horizontal lines the paths of movements of the various yarn carriers indicated therein, the yarns carried by these car-

riers being designated at the left hand side of this figure. The extents of the various groups of needles forming the fourth, third, second and first fingers and the thumb are indicated by the columns extending vertically in Figure 7. The same columns are continued through Figure 8. The range of movement of a particular yarn carrier is determined by the positions of its corresponding cams 90 and 92, which are illustrated on the horizontal lines of Figure 7 by the short vertical strokes. The figure accordingly indicates that the yarn carrier 30 is capable of moving from a position to the left of the fourth finger needles to a position to the right of the thumb needles under the action of its driving lever 78. Similarly the fourth finger yarn carrier 32 moves from a position to the left of the fourth finger needles to the right thereof, the second finger yarn carrier moves from a position to the left of the second finger needles to the right thereof, the third finger yarn carrier moves from a position to the left of the third finger needles to the right thereof, the first finger yarn carrier moves from a position to the left of the first finger needles to the right thereof and the thumb yarn carrier moves from a position to the left of the thumb needles to the right thereof. It will be noted that the ranges of movements of the fourth finger, second finger and thumb yarn carriers do not overlap, the same being true of the third and first finger yarn carriers.

With the above explanation, the preferred method of formation of a glove may be readily understood, considering initially the first course of the inner palm portion 152 at the wrist line 150. In the formation of this portion of the glove, the needles initially raised into action by the controlling jacquard mechanism are those which are adapted to form the first, second and third fingers. The palm yarn carrier 30 prior to the formation of this course has occupied an inoperative position indicated at 163 in Figure 8, in which position it was located at a position above the first finger needles, this position being held due to the left hand and upper position of its bar 28. The first action, therefore, is to effect the right hand and downward movement of this bar, which moves the palm carrier to a position indicated at 163 to the right of the thumb needles, all of the other fingers being now raised out of action by the proper location of their supporting bars.

Reciprocation of the palm yarn carrier now takes place as indicated at 170, the carrier moving completely across the entire set of needles. Initially, however, only the needles of the first, second and third fingers are raised as indicated above, so that a narrow tube is knit, the needles on one side receiving yarn as the carrier moves to the left and the needles on the other side receiving yarn as the carrier moves to the right. As the knitting of the inner palm proceeds, needles are added in pairs at the ends of the active set, so that widening is produced as indicated at 151. Eventually, all of the needles which are to be active are receiving yarn so that the full width tube is formed providing the inner portion of the palm inside the thumb. The movements of the palm yarn carrier are indicated diagrammatically at A in Figure 8. Ultimately, when the line 154 is reached, corresponding to the course just prior to the formation of the thumb, the bar carrying the palm yarn carrier 30 is moved upwardly and to the left to take this yarn carrier out of action after it

has been moved to its extreme right hand position. The position of the carrier when so put out of action is indicated at 172.

Before the next course, the thumb yarn carrier is first moved downwardly to the left to move the thumb yarn carrier from its inoperative position 174 to its initial operative position 176. Thereafter, it is moved as indicated at 178 through a complete stroke back to the position 180 where it is disengaged by its lever 98 and thereafter it is raised to inoperative position to the right as indicated at 182 by a right hand movement of its carrier bar. During this reciprocation of the thumb yarn carrier, the only needles which are raised to take the yarn are the thumb needles, the others being located out of action so that even though the carrier 40 passes the yarn over the first finger needles, these needles cannot take the yarn, with the consequence that a clean left hand boundary 20 for the thumb is provided.

After this action, the palm finger is again brought into action and given one complete stroke as indicated at 184. During this stroke the thumb needles are not raised, while the remaining needles are raised so as to form the tubular outer palm portion indicated at 156. By alternating the actions just described of the thumb and palm yarn carriers as indicated in the region B of Figure 8, alternate courses form 30 the thumb 158 and the outer palm portion of the glove 156, the two tubes thus simultaneously formed being completely separated from each other due to the needle selection.

This action continues until the course indicated at 160 is reached. Thereupon, as indicated at 186, 188 and 190, the thumb, second and fourth finger yarn carriers, respectively indicated at 40, 34 and 32, are brought into action by the proper movements of their supporting bars and 40 are given simultaneous complete strokes to form courses of three tubes providing thumb, second and fourth fingers. During this operation, only the thumb, second finger and fourth finger needles are raised into action, the first and third 45 finger needles remaining out of action so that even though the yarn carrier movements overlap these needles no knitting occurs thereby. After the course thus formed, the three yarn carriers are raised out of action and the first and third 50 finger yarn carriers are brought into action and given simultaneous complete strokes, as indicated at 192 and 194, the first and third finger needles being now active while the thumb, second and fourth finger needles are inactive. 55 Thus courses of the first and third finger tubes are formed. These alternate series of courses, indicated at C in Figure 8, are repeated until there is reached the position indicated at 162 at which the formation of the thumb tube is to 60 cease. At this point, therefore, the thumb yarn carrier is permanently raised out of action. In the next course the thumb needles are raised and again lowered to cast off the loops so that during subsequent knitting the thumb portion 65 is not held on the needles. The formation of alternate pairs of courses continues, the second and fourth finger yarn carriers forming simultaneously their respective courses, and the first and third finger yarn carriers forming theirs. 70 These alternate courses are indicated diagrammatically at D in Figure 8.

This action continues, overlap being prevented by the raising of the proper needles during the formation of the alternate courses, until the 75

course position indicated at 164 is reached, at which position the formation of the fourth finger should cease. In order to cast off the loops held by the fourth finger needles, an idle course of 5 operation of the machine is effected in which these needles are raised and then lowered. At this time no yarn should be fed to the needles and consequently neither the third nor fourth finger yarn carriers should reciprocate at this 10 time. This idle condition may be effected with the provision of an additional control position of the cam 88 by having the thumb carrier idly move in this course. Since no needles are raised to take the yarn of the thumb carrier, no knitting 15 occurs. From this position 164 until the position 150 is again reached, only the first, second and third fingers are formed, although the first, second, third and fourth finger carriers are reciprocated, the further formation of the 20 fourth finger being prevented merely by jacquard control of the fourth finger needles to keep them inoperative. Inasmuch as relatively few courses are formed, there is no objection to the idle reciprocation of the fourth finger yarn carrier, though 25 it will be obvious that by additional control through the cams on plate 88 and/or the raising of the fourth finger carrier bar, it could be rendered inoperative in the same fashion as the thumb yarn carrier.

30 After the first, second and third finger tubes are completed, the position 150 is reached and the next glove formed in the fashion described above. It may be noted that the needles which became inoperative at cessation of formation of 35 the thumb and fourth fingers are brought into action one by one on each side during the widening process referred to above.

During the operations mentioned above, selective reciprocations of the yarn carriers are 40 controlled by the selective positioning of cam plate 88, the action of which will be clear from consideration of the cams 112 thereon as illustrated in Figure 6.

The gloves are thus formed in a continuous 45 strip, as indicated in Figure 1. The gloves are cut from the strip along the lines 150 and the various fingers closed by stitching, the wrist being likewise finished by stitching.

It will be obvious that some slight simplification 50 of the machine may be effected if, instead of forming the portion between the lines 160 and 162 of Figure 1 in two alternate courses, three alternate courses are provided, one for the formation of the thumb tube, one for the formation of 55 the first and second finger tubes and one for the formation of the second and fourth finger tubes. While this makes it possible to eliminate the double cam arrangement illustrated in Figure 6 and so simplifies somewhat the machine construction 60 (making it necessary to provide only six rods 104, for example) it will be obvious that during formation of this portion of the glove by such method a longer time will be required than in the preferred method detailed above.

65 While there has been specifically described the alternating of single courses to form the various portions of the glove, it will be obvious that variations from this are possible within the scope of the invention. For example, two, or even three, 70 courses might be successively formed in the thumb portion and then the same number in the outer palm portion with these groups of courses, rather than single courses, alternated, thus simplifying the pattern control of the machine. However, if 75 groups of courses are thus formed, the groups

cannot be too great, since otherwise stretching and distortion of the portion held upon idle needles will occur. When the loops formed are small, however, such groups of pluralities of courses may be alternated. It will be understood, therefore, that where alternation is referred to in the claims it is intended that there should be included the alternations of groups of pluralities of courses.

While the machine has been specifically disclosed adapted for the formation of gloves, it will be obvious that it may be used in other fashions. In fact, it need not be restricted to the formation of tubular fabric, since, as will be obvious from my other patent, the same machine 10 by a proper control of the needles may be made to form flat fabrics containing patterns. In such cases, the machine may be used to form narrow portions as continuations of wider portions by the type of alternation of courses indicated above. 15 In any case, whether flat or tubular fabric is formed, the invention permits the knitting of two adjacent separate portions on groups of needles with the adjacent needles of the two groups no more spaced from each other than any other 20 needles of the machine, that is, all of the needles may be operated with no idle needles between the groups forming the separate portions.

What I claim and desire to protect by Letters 30 Patent is:

1. The method of knitting gloves comprising knitting a tube to provide first a wrist portion, and then, by gradual widening, an inner palm portion, then knitting in alternate courses, and continuously with the inner palm portion, continuations of said inner palm portion to form an outer palm portion and a thumb portion, thereafter knitting in one of alternate courses of knitting a continuation of said thumb portion and, simultaneously, two tubular extensions of the outer palm portion to provide second and fourth finger portions, and in the other of said alternate courses of knitting two further tubular extensions of the outer palm portion to provide first and third finger portions, interrupting knitting of said thumb portion while continuing knitting in alternate courses of the second finger portion and the first and third finger portions, and thereafter knitting as a continuation of the first, second and third finger portions the wrist portion of a subsequent glove.

2. The method of knitting gloves comprising knitting a tube to provide first a wrist portion, and then, by gradual widening, an inner palm portion, then knitting continuously with the inner palm portion and by alternating sequence of courses continuations of said inner palm portion to form an outer palm portion and a thumb portion, thereafter knitting by alternating sequence of courses continuations of the thumb and outer palm portions to provide thumb and finger portions, courses of the thumb, second and fourth finger portions being formed simultaneously and courses of the first and third finger portions being formed simultaneously, interrupting knitting of said thumb portion while continuing the alternate knitting of said finger portions, then interrupting knitting of said fourth finger portion while continuing the alternate knitting of the other finger portions and thereafter knitting as a continuation of the first, second and third 75

finger portions the wrist portion of a subsequent glove.

3. The method of knitting gloves comprising knitting a tube to provide an inner palm portion, then knitting continuously with the inner palm portion and by alternating sequence of courses continuations of said inner palm portion to form an outer palm portion and a thumb portion, and thereafter knitting by alternating sequence of courses continuations of the thumb and outer palm portions to provide thumb and finger portions. 10

4. The method of knitting gloves comprising knitting a tube to provide an inner palm portion, then knitting continuously with the inner palm portion and by alternating sequence of courses continuations of said inner palm portion to form an outer palm portion, a thumb portion, and finger portions, and thereafter knitting as a continuation of the first, second and third finger portions the wrist portion of a subsequent glove. 15

5. The method of knitting gloves comprising knitting a tube to provide an inner palm portion, then knitting continuously with the inner palm portion and by alternating sequence of courses continuations of said inner palm portion to form an outer palm portion and a thumb portion, thereafter knitting by alternating sequence of courses continuations of the thumb and outer palm portions to provide thumb and finger portions, courses of the thumb, second and fourth finger portions being formed simultaneously and courses of the first and third finger portions being formed simultaneously, and thereafter knitting as a continuation of the first, second and third finger portions the wrist portion of a subsequent glove. 20

6. The method of knitting gloves comprising knitting a tube to provide an inner palm portion, then knitting continuously with the inner palm portion and by alternating sequence of courses continuations of said inner palm portion to form an outer palm portion and a thumb portion, thereafter knitting by alternating sequence of courses continuations of the thumb and outer palm portions to provide thumb and finger portions, courses of at least the second and fourth finger portions being formed simultaneously and courses of the first and third finger portions being formed simultaneously, and thereafter knitting as a continuation of the first, second and third finger portions the wrist portion of a subsequent glove. 25

7. The method of knitting gloves comprising knitting a tube to provide an inner palm portion, then knitting continuously with the inner palm portion and by alternating sequence of courses continuations of said inner palm portion to form an outer palm portion and a thumb portion, and thereafter knitting by alternating sequence of courses continuations of the thumb and outer palm portions to provide thumb and finger portions, courses of at least the second and fourth finger portions being formed simultaneously and courses of the first and third finger portions being formed simultaneously, interrupting knitting of said thumb portion while continuing the alternate knitting of said finger portions, then interrupting knitting of said fourth finger portion while continuing the alternate knitting of the other finger portions. 30

8. The method of knitting gloves comprising knitting a tube to provide first a wrist portion, and then, by gradual widening, an inner palm portion, then knitting continuously with the inner palm portion and by alternating sequence of courses continuations of said inner palm portion to form an outer palm portion and a thumb portion, thereafter knitting by alternating sequence of courses continuations of the thumb and outer palm portions to provide thumb and finger portions, courses of at least the second and fourth finger portions being formed simultaneously and courses of the first and third finger portions being formed simultaneously, interrupting knitting of said thumb portion while continuing the alternate knitting of said finger portions, then interrupting knitting of said fourth finger portion while continuing the alternate knitting of the other finger portions, and thereafter knitting as a continuation of the first, second and third finger portions the wrist portion of a subsequent glove. 35

9. The method of knitting gloves comprising knitting a tube to provide first a wrist portion, and then, by gradual widening, an inner palm portion, then knitting continuously with the inner palm portion and by alternating sequence of courses continuations of said inner palm portion to form an outer palm portion and a thumb portion, thereafter knitting by alternating sequence of courses continuations of the thumb and outer palm portions to provide thumb and finger portions, courses of at least the second and fourth finger portions being formed simultaneously and courses of the first and third finger portions being formed simultaneously, interrupting knitting of said thumb portion while continuing the alternate knitting of said finger portions, then interrupting knitting of said fourth finger portion while continuing the alternate knitting of the other finger portions. 40

10. The method of knitting tubular fabric on a knitting machine comprising forming a tube on a group of needles thereof, and forming a plurality of narrower tubes as continuations of the first tube on sub-groups of said group of needles, said continuations being formed by alternate knitting of courses thereof, the sub-group of needles forming one continuation being out of action during the formation of an adjacent continuation. 45

11. A knitting machine comprising a group of needles including at least two sub-groups the end needles of which are closely adjacent each other, yarn carriers movable along the group of needles and adapted to selectively feed yarns to the needles of said sub-groups, and means for alternately actuating said yarn carriers for the alternate formation of courses by the needles of said sub-groups with the yarns forming courses on one sub-group not extending across wales 50 formed by another sub-group. 55

12. A knitting machine comprising a group of needles including at least two sub-groups the end needles of which are closely adjacent each other, yarn carriers movable along the group of needles and adapted to selectively feed yarns to the needles of said sub-groups, and means for alternately actuating said yarn carriers for the alternate formation of courses by the needles of said sub-groups, the carrier which is out of action being moved transversely to the direction of motions of the carriers to provide free passage 65 for the other carrier. 70

13. A knitting machine comprising a group of needles including at least two sub-groups, the 75

- end needles of which are closely adjacent each other, means for feeding yarns to each of said sub-groups to form alternately courses on said sub-groups with the yarns forming courses on one sub-group not extending across wales formed by another sub-group, and means for effecting selective operations of the needles so that the needles of each sub-group fail to take yarn while yarn is being fed to the needles of the other.
- 10 14. A knitting machine comprising a group of needles including at least two sub-groups, the end needles of which are closely adjacent each other, means for feeding yarns to each of said sub-groups alternately during the formation of 15 courses by the machine with yarns forming courses on one sub-group not extending across wales formed by another sub-group, and means

for effecting selective operations of the needles so that the needles of each sub-group fail to take yarn while yarn is being fed to the needles of the other.

15. A knitting machine comprising a group of 5 needles arranged to form a tube of fabric and including at least two sub-groups arranged to form small tubes of fabric as continuations of the first mentioned tube, the end needles of said sub-groups being closely adjacent each other, 10 means for feeding yarns to each of said sub-groups to form alternately courses on said sub-groups, and means for effecting selective operations of the needles so that the needles of each sub-group fail to take yarn while yarn is being 15 fed to the needles of the other.

HYMAN M. ZIPPEL.
